UNITED STATES PATENT OFFICE.

JOSEPH O. CADIEUX, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

SIGNAL STATION.

Application filed June 27, 1923. Serial No. 647,994.

To all whom it may concern:

Be it known that I, JOSEPH O. CADIEUX, a citizen of the United States of America, residing at Meriden, New Haven County, Connecticut, have invented a new and useful Signal Station, of which the following is a specification.

My invention relates particularly to a construction adapted to be used with a hospital 10 signal system embodying a plurality of signal lights and also preferably a switch.

The main object is to provide a simple, compact, construction of neat design which may be readily installed and inspected, and 15 in which the signal lights may be readily replaced without the use of tools.

Figure 1 is a front view of one form of construction embodying improvements of my invention.

20 Fig. 2 is a perspective view showing the cover opened.

Fig. 3 is a transverse sectional view showing the latch.

The baseplate 5 may be of any suitable 25 construction for instance of metal adapted to support a plurality of lamp sockets 6 and their bulbs 7.

In this particular construction I have also provided a switch 8 having a push and pull 30 operating member 9 for controlling one of the circuits in the system. The baseplate is adapted to be secured to a wall in any suitable manner for instance by means of a plurality of screws (not shown) in holes such as 10.

The cover plate 11 is adapted to snugly fit 40 against the baseplate and is preferably hinged thereto at 12 at one end and provided at the other end with some form of catch. In this instance I have provided a concealed 45 catch consisting of a ball member 13 secured to the cover and spring clips 14 secured to the baseplate. For convenience in construction the clips 14 are mounted in a pocket 15 which is secured to the baseplate and extends to the rear thereof. For convenience in disengaging the catch I may provide a finger recess 16 adjacent the catch.

A cover is also provided with bull's-eyes 50 or glasses such as 18 to correspond with va-

rious lights carried by the baseplate. These glasses may be provided with indicating numbers, letters, or other means for distinguishing between the various lights, or the lights themselves may be of different colors. 55 The cover is also provided with an opening 19 to allow for the handle 9 of the switch.

The station is so wired as to light the proper light at the proper time for signalling purposes. In case it becomes necessary to inspect the lamps or replace one or more of them, access may be readily had by simply swinging the cover outwardly so as to display the baseplate and the lamps. It will be noted that the construction is such that all 60 the attaching screws are concealed when the cover is in place so that the effect is one of neatness and cleanliness.

I claim:

1. A signal station comprising a base 70 plate having a plurality of lamp sockets, supported by the base plate and extending rearwardly therefrom back of corresponding openings therein to receive lamps with their forward ends back of the face of the base plate, means for securing said sockets to said base plate, and a cover plate hinged to said base plate to swing thereagainst to conceal the means of securing said sockets, and having windows to register with said sockets. 75

2. A signal station comprising a base plate, a lamp socket supported thereby projecting rearwardly therefrom, back of an opening therein to receive substantially all of a lamp, a switch, means for securing said lamp socket and said switch to said base plate, a cover plate hinged to said base plate and concealing said securing means, and having a window in register with said socket and an opening, said switch having an operating member projecting through said opening when said cover plate is closed. 85

3. A signal station comprising a base plate, a plurality of lamp sockets carried thereby and extending rearwardly therefrom so that lamps carried thereby will be mainly at the rear of the base plate, a switch carried by said base plate and having an operating member, a cover plate to be secured to said base plate and having bull's-eye glasses to 95 100

register with said sockets and having an opening for said switch operating member.

4. A signal station comprising a base plate, having perforations for use in fastening the same substantially flush with a wall, a plurality of lamp sockets projecting rearwardly from the base plate to support forwardly

extending lamps back of the face of the base plate, and a cover plate hinged to said base plate to normally conceal said perforations and having glass windows in register with said sockets and means for holding said cover plate closed.

JOSEPH O. CADIEUX.
